DESIGN FOR A ROLLING TOY

Joseph Davis, Arlington, N. J., assignor to Joseph Davis Plastics Co., Arlington, N. J., a corporation of New Jersey

Application January 15, 1948, Serial No. 143,819

Term of patent 14 years

(Cl. D34—15)

To all whom it may concern:

Be it known that I, Joseph Davis, a citizen of the United States, residing in Arlington, county of Hudson and State of New Jersey, have invented a new, original, and ornamental Design for a Rolling Toy, of which the following is a specification; reference being had to the accompanying drawing, forming a part thereof:

Fig. 1 is a side elevational view of a rolling toy embodying my new design, and

Fig. 2 is an end elevational view thereof looking in the direction of the arrows on line 2—2 of Fig. 1.

I claim:

The ornamental design for a rolling toy, as shown.

JOSEPH DAVIS.
